UNITED STATES PATENT OFFICE.

HANS OTTO SWOBODA, OF NEW YORK, N. Y., ASSIGNOR TO THE GENERAL INCANDESCENT ARC LIGHT COMPANY, OF NEW YORK.

ELECTRIC-ARC LAMP.

SPECIFICATION forming part of Letters Patent No. 533,100, dated January 29, 1895.

Application filed March 2, 1894. Serial No. 502,047. (No model.)

To all whom it may concern:

Be it known that I, HANS OTTO SWOBODA, a subject of the Emperor of Germany, residing in the city of New York, in the county 5 and State of New York, have invented a certain new and useful Improvement in Electric-Arc Lamps, of which the following is a specification.

I will describe a lamp embodying my invention and then point out the novel features in claims.

In the accompanying drawings, Figure 1 is a side elevation of a lamp embodying my improvement. Fig. 2 is a side view of the lamp 15 in a plane at right angles to Fig. 1. Fig. 3 is a side elevation of certain parts on the opposite side of the lamp to that which is illustrated in Fig. 1. Fig. 4 is a vertical section of an armature or core of modified construction. Fig. 5 is a side view of certain parts of the lamp illustrating a modification. Fig. 6 is a side view of certain parts of the lamp 20 illustrating a modification. Fig. 7 is a top view of the body piece of a spool for a solenoid. Fig. 8 is a plan of a detachable flange for said spool. Fig. 9 is a perspective view 25 illustrating the manner in which the detachable flange may be engaged with the body piece of the spool.

30 Similar letters of reference designate corresponding parts in all the figures.

As my improvement does not relate to the circuit of the lamp or to the construction of the frame, I shall not describe these features 35 except incidentally in explaining other parts.

A' A² designate two rods extending from a plate A down to a holder for the lower carbon. As the latter may be of any suitable construction, I have not shown it. One of 40 the rods A' A² may be hollow to receive a circuit wire B, covered with insulating material.

C designates another plate which is connected to the plate A, by means of intermediate rods, or otherwise. It is shown as having 45 a central hub in which a rod D, is fitted. The rod D may serve as a support for the lamp. I have shown the plate C as provided with binding screws c' c² for the connection of the circuit or line wires leading to and from 50 the lamp. I may add that both these binding

screws are insulated from the plate C. The wire B, is connected with the binding screw c'.

I will now particularly describe the form of lamp illustrated by Figs. 1, 2, 3 and 4.

E designates a rod which is to be provided 55 at the lower end with a holder for the upper carbon, its office being to support said carbon. It will be seen that this rod is provided with a rack e on one side and that it moves upwardly through a hole in the center of the 60 plate A. It may be guided by a bearing in a plate F, which is mounted upon the plate A, and also by a bearing in a plate F' which is supported above the plate F and connected with it by means of two vertical plates or 65 pieces F² F³. This rod may also pass upwardly through the plate C and into the rod D, providing the latter is made tubular, which will preferably be the case. The downward movement of the rod may be limited by a 70 stop-pin arranged in its upper portion, so that it may contact with the plate F'.

With the rack e of the rod E, engages a gear wheel G, which is supported in bearings with which the side pieces F² F³ are provided. 75 As here shown these bearings consist of screws passing through the side pieces and engaging with the ends of a shaft g, upon which the said gear wheel is affixed.

The shaft g forms a support for an oscillating frame H, here shown as consisting of two angular or L-shaped side pieces h' h², and intermediate cross-pieces or stretchers h³. As here shown, these side pieces are loosely mounted upon this frame and loosely mounted 85 upon the said shaft g.

G' designates a pinion affixed to a shaft g' journaled in the side pieces of the frame H. On the same shaft is affixed a gear wheel G². When the rod E is moved in either direction, 90 it will rotate the pinion G', and consequently the gear wheel G². The gear wheel G² engages with a pinion G³, affixed to a shaft g³, which is journaled in bearings in the side pieces of the frame H. On the shaft g³ is affixed a 95 brake wheel G⁴, and with this I combine a brake lever G⁵, having one arm which is curved to conform to the periphery of the brake wheel. If desired, one of these parts may be grooved and the other constructed to 100

enter such groove. The brake lever G^5 is fulcrumed by a screw or pin g^3 to one of the side pieces of the frame H. One of the arms of the lever is connected to a spring g^5 , which is 5 also connected to the frame H. Of course, if the lever is properly weighted the spring may be dispensed with. The spring is so combined with the lever as to apply it to the brake wheel when the frame H is in that position 10 which it occupies when there is no current on the lamp and at such times as there is a great resistance in the arc. That end of the brake lever which acts upon the brake wheel, is shown as provided with a projection g^6 , which 15 may be made in the form of an adjustable screw, engaging with a tapped hole in the end portion of said lever. The stationary frame F F' F² F³ is provided with a projection f . When the frame H rocks forward, the projection g^6 impinges against the projection f , and thus the brake lever will be operated so as to release the brake wheel, whereupon the upper carbon may feed downwardly. When 20 the frame H is oscillated in the reverse direction, the projection g^6 will leave the projection f , and the spring g^5 will apply the brake lever again to the brake wheel.

The frame H is connected with the core or armature J' of a solenoid or magnet J. 30 When made for an alternating current lamp this core J' is composed of a number of iron wires j , insulated from each other in any suitable manner, as, for instance, by being coated or oxidized. If desired, these wires may all 35 be surrounded by a single glass sleeve. These wires j are fitted at their ends into cap-pieces j' j^2 which may be made of insulating material or metal, but if metal is employed and the lamp is intended for an alternating 40 current, there should be a split in each of the cap-pieces lengthwise of the core and to the center. I do not want to be limited, however, to the use of a core made in this manner, as I may use a solid iron core, or a laminated iron core. If a solid iron core is used 45 and the lamp is employed for an alternating current, the core should be split lengthwise.

The core J' works within the solenoid or magnet J, which may have a series or differential winding. This winding will be connected in the lamp circuit in any suitable manner. As here shown, one of the wires extending from the winding connects with one 50 of the side pieces F² F³ of the frame F F' F² F³. Obviously, the horseshoe form of magnet, instead of the solenoid form, may be employed.

When the solenoid or magnet J, draws its core or armature upward, the frame H will be 60 oscillated in such direction as to effect an upward movement of the rod E, and consequently, of the upper carbon. This is produced through the engagement of the pinion G' and gear wheel G, with the rod E. In this 65 way the arc is established. As the resistance of the arc increases, the core or armature will

be allowed to move downward so as to lower the upper carbon. On moving down far enough, it will cause the gearing to be released, so that the rod E may feed downward. 70

Preferably a dash-pot K will be combined with the frame H and some stationary part of the lamp frame. In the present instance its cylinder is connected to an appurtenance of one of the side pieces F² F³ of the frame F F' F² F³, and its piston to a lateral extension on the frame H. The purpose of this dash-pot is to prevent too sudden movements of the frame H.

In the form of lamp shown by Figs. 1 and 80 2, the circuit extends through the frame F F' F² F³ and from such frame, by means of a metal brush L, to the rod E, which carries the upper carbon.

The frame H while, generally speaking, being L-shaped as in the first described example of my improvement, may have its arm h' , which extends in the main horizontally, adjustable relatively to the other arm h^2 . As here shown, both arms are loosely mounted 90 upon the shaft g and the side pieces of the frame constituting the arm h' , lap over the side pieces constituting the arm h^2 , and where the lap occurs, the side pieces constituting the arm h' have arc-shaped slots h^4 that are concentric with the shaft g and are combined with clamping screws h^5 . By this construction of the L-shaped frame H, provision is afforded for adjusting its two arms relatively to each other at different angles, and thus the 100 lamp may be varied to suit different currents, for, obviously, the more the upright arm on the L-shaped frame H is adjusted outwardly, or, in other words, toward a horizontal position, the greater effect will its weight have in 105 opposing the magnet or solenoid J.

For connecting the frame H, with the armature or core of the magnet or solenoid, I use a link L', having a pivotal connection at one end with the frame H, and provided with a 110 longitudinal row of holes which afford provision for engaging the link at different points in its length, with the armature or core, by means of a transverse pin passing through a hole in the armature or core and one of the 115 holes in the link. By changing the point of connection between the link and the core, provision is afforded for tilting the frame H more or less, to vary the opposing force which its weight offers to the magnet or solenoid. 120

It is not necessary to make the frame H adjustable in itself, if provision is afforded for adjusting its connection with the armature or core.

Turning now to Fig. 5, it is only necessary 125 to say that it illustrates the substitution for the rack bar and gear wheel E, G of a spring barrel M, having its periphery constructed on the principle of a fusee barrel, or, in other words, with a groove of varying diameter, so 130 as to equalize the varying action of the spring, and a cord or strap wound upon said spring

barrel and connected with a carbon support or carrier, which will be provided with the holder for the upper carbon. This carrier is fitted to any suitable frame work, so as to be 5 properly guided in its movements. It is intended to be heavy enough to overcome the tension of the spring barrel, so that whenever it is unrestrained it will descend.

In Fig. 6, I have shown two movable carbon supports or carriers N' , N^2 , which will be provided with holders for upper and lower carbons. These carriers are fitted to any suitable frame-work N , so as to be properly guided in their movements. N^3 is a guard or 10 equivalent device, connected at the ends to the two carriers N' N^2 and intermediately passed around a wheel N^4 . The upper carbon carrier N^2 is intended to be heavier than the lower, so that whenever it is unrestrained it 15 will descend and by its descent raise the lower carbon. The wheel N^4 is intended to be mounted upon a shaft corresponding to the shaft g in the lamps already described, and to be controlled in its movements by a train of 20 wheels such as I have illustrated in the two different examples of my improvement shown by Figs. 1, 2, 3 and 4, in connection with a magnet or solenoid with an armature or core.

The drum which I have described in connection with Fig. 6, is to all intents and purposes, a wheel which is connected with a movable support for a carbon and hence it corresponds in effect with the wheel G , illustrated in the first and second examples of my 25 improvement. The wheel of Fig. 7 also corresponds with the said drum and with the said wheel G , in the sense of being a wheel which is connected with a movable support for a carbon. Each of these devices may be 30 designated as a device for controlling a movable support for a carbon.

I have shown the solenoid as provided with a spool S , having a body s made of metal, with flanges s' , s^2 at the top and bottom. 35 When the lamp is intended for an alternating current the body of this spool will be split lengthwise from end to end, in the man-

ner represented at the lower portion in Fig. 2. In addition to the flanges s' s^2 , the spool may have large flanges of insulating material 50 s^3 s^4 , and these may be slipped over the upper flange s' , if such upper flange be notched in the manner represented in Fig. 7 and the flanges are notched in the manner represented in Fig. 8, for then each flange may be slipped over the flange s' in the manner indicated in Fig. 9.

What I claim as my invention, and desire to secure by Letters Patent, is—

1. In an arc lamp, the combination of a 60 movable carbon support, stationary supporting pieces, a tilting frame pivotally supported in said stationary supporting pieces, a pivoted arm for moving said tilting frame, adjustably attached thereto and having its pivotal axis identical with the axis of movement of said tilting frame, a brake and brake wheel carried by said tilting frame and moving with the latter when the same is moved, mechanism connecting the brake wheel with 65 the movable carbon support, a magnet or solenoid for moving said tilting frame by means of said adjustable arm, and a fixed stop for coacting with an adjustable extension of said brake, substantially as specified. 70

2. In an arc lamp, the combination of a 75 movable carbon support, a device for controlling the movement of such support, a tilting frame, and a solenoid whose core controls the movement of the tilting frame, said solenoid 80 including a spool having a body portion and removable end flanges, said body portion being so formed as to permit the suitably notched flanges to be slipped on, and locked on a partial rotation of the same, substantially as specified. 85

In testimony whereof I have signed my name to this specification in the presence of two subscribing witnesses.

HANS OTTO SWOBODA.
